UNITED STATES PATENT OFFICE.

JAMES H. GORDEN, OF COOPER, TEXAS, ASSIGNOR OF ONE-HALF TO
JAMES PATTESON, OF COOPER, TEXAS.

TELEPHONE SYSTEM.

No. 821,482.

Specification of Letters Patent.

Patented May 22, 1906.

Application filed June 10, 1903. Serial No. 180,939.

To all whom it may concern:

Be it known that I, JAMES H. GORDEN, a citizen of the United States, residing at Cooper, in the county of Delta and State of Texas, have invented a new and useful Telephone System, of which the following is a specification.

This invention relates to telephone systems, and particularly to that general class of lockout systems wherein provision is made for locking the receiver-hooks at all substations between two connected stations, thus preventing overhearing of a conversation.

A further object of the invention is to provide a system in which the line may be subdivided to permit its use for more than one message at the same time—that is to say, any two connected subscribers will monopolize only that portion of the line between their two stations, while the line beyond each of the two connected subscribers is still open for use.

With these and other objects in view, as will more fully hereinafter appear, the invention consists in certain novel features of construction and arrangement of parts hereinafter fully described, illustrated in the accompanying drawings, and particularly pointed out in the appended claims, it being understood that various changes in the form, proportions, size, and minor details of the structure may be made without departing from the spirit or sacrificing any of the advantages of the invention.

In the accompanying drawings, Figure 1 is a diagram illustrating a number of stations connected in accordance with the invention. Fig. 2 is a similar view, on an enlarged scale, of one of the stations, showing the positions which the parts occupy when not in use. Fig. 3 is a view similar to Fig. 2, showing the position to which the receiver-hook is moved when the subscriber wishes to talk to a station to the right. Fig. 4 is a similar view illustrating the position assumed by the receiver-hook when the subscriber wishes to talk to a station on the left. Fig. 5 is a detail view of the receiver-hook-locking mechanism.

Similar numerals of reference are employed to indicate corresponding parts throughout the several figures of the drawings.

Each substation has a telephone provided with three binding-posts 1, 2, and 3, of which the binding-posts 1 and 3 are connected to a

line-wire 4, and a local connection between 55 the binding-posts 1 and 3 places all of the phones along the line in series. The central binding-post 2 is grounded or connected to a metallic return, as desired, and this connection is such that all of the telephones along 60 the line are bridged or, as will more fully hereinafter appear, the normal circuit through the phones when a call is sent along the line is in series, while in making a call at a particular station or in talking from that station the 65 telephone is bridged either between the line-wire and ground or between the line-wire and the metallic return, as the case may be.

Each of the local stations is provided with a receiver 6, an induction-coil 7, a magneto-generator 8, a call-bell 9, and a transmitter 10, all of which may be of the usual construction.

At each local station is a receiver-hook 11, which may be of the usual construction and provided with a suitable spring for raising 75 the outer end of the hook when the receiver is removed. In the switch-box of each telephone, preferably at a point below the receiver-hook, are arranged a number of contacts 12, 13, 14, 15, and 16 and an additional 80 contact 11', that may be said to form a part of the receiver-hook, this contact being connected to said receiver-hook by a link 50.

When the receiver is on the hook and the parts are in the normal position (shown in 85 Fig. 2,) the receiver-hook contact 11' and the contacts 12, 13, and 14 are all electrically connected, while the contacts 15 and 16 are spaced from each other and from the receiver-hook contact. This being the normal position, it will be seen on reference to Fig. 2 that the circuit through the telephone is completed and the connection between two stations—one to the right and one to the left of the station shown in Fig. 2—is in series. This 90 talking-circuit may be traced through a wire 22 and electromagnet 23 to contact 14, contact 12, and wire 17 to binding-post 3 and the main line, showing that the circuit through the station is completed and that at this station the electromagnet 23 will be energized 95 and will remain energized so long as any two subscribers on opposite sides of said station are talking, the primary batteries of the connected stations, as will appear hereinafter, 100 being connected in series with the line and being of sufficient strength to energize the electromagnets. In each local station is a

105

receiver-hook-locking catch 27, which may be formed of soft iron and is disposed within the field of force of the electromagnet 23. When the electromagnet is energized, this catch is moved from the receiver-hook and prevents raising of the latter and the over-hearing of any conversation by a subscriber between two connected stations. At a point adjacent to the electromagnet is arranged a second catch 28, that is operable by a projecting knob extending outside the switch-box. This catch 28 normally lies in the path of movement of the receiver-hook switch and limits upward movement of the latter under ordinary conditions—that is to say, if the receiver is removed from the hook the latter will be elevated until it strikes the lower end of the catch 28, as shown in Fig. 3. Under certain conditions, however, it may be desired to allow further upward movement of the receiver-hook, and this is accomplished by moving the catch 28 outward, so that said hook can raise to the position shown in Fig. 4. The catch 28 is under the control of the subscriber; but the catch 27 is not, and during the time a conversation is being carried on between two subscribers all of the electromagnets at intermediate stations will be energized and the catches 27 attracted to receiver-hook-locking positions.

The receiver-hook controls two pole-changers 30 and 31, each of which consists of two spring-contact plates adapted to be moved into engagement with each other by the receiver-hook. When the receiver-hook moves up to the first position, (indicated in Fig. 3,) the two contacts of the pole-changer 30 will be engaged, while the contacts 31 will remain open. When moved up to the highest position, (shown in Fig. 4,) the two contacts 31 will be engaged and the contacts 30 will be open. This gives two directions from battery to ground. The ground-wire 33 is connected to binding-post 2, and from binding-post 2 leads a wire 34 to the primary of the induction-coil 7. From the induction-coil lead two wires 35 and 36, one to the pole-changer 30 and the other to the pole-changer 31. From the pole-changer 30 leads a wire 31' through the transmitter 10 to one side of the battery 26, and from the opposite side of the battery leads a wire 35 to the pole-changer 31. The wire 35 is connected by a wire 37 to contact 13, and the wire 31 is connected by a wire 38 to contact 16. Leading from the wire 34 is a wire 40, that is connected to the bell, condenser 19, magneto-generator 8, and wire 41 to the receiver-hook contact 11'. From the wire 22 at a point adjacent to the binding-post 1 leads a wire 43 to contact 15, and from the binding-post 3 leads a wire 17 to the contact 12. It will be observed that the receiver 6 is connected in a strictly local circuit with the secondary of the induction-coil by a wire 45.

Should any subscriber wish to converse with any station to the right of his own station, he removes the receiver from the hook and allows the same to raise into engagement with the catch 28. This connects the two contacts of the pole-changer 30, and the limited upward movement is just sufficient to disengage the contact 12 from the contact 14, the three contacts 11', 12, and 13 remaining in engagement with each other. The subscriber then turns his magneto-generator, and the signaling-circuit is established from the ground-wire 33, binding-post 2, wire 34, wire 40, call-bell 9, condenser 19, magneto-generator 8, coil 41, contact 11', contacts 13 and 12, and wire 17 out through the main line 4 to the right. To each of the stations on the right the circuit is continued through binding-post 1, wire 22, electromagnet 23, contact 14, contacts 12 13 11', to wire 41, magneto-generator 8, wire 40, condenser 19, call-bell 9, wire 40, wire 34, binding-post 2 to ground-wire 33, all of the stations to the right being thus bridged between the main line and the ground. The series circuit is still established through wire 22, electromagnet 23, contact 14, contact 12, wire 17, and binding-post 3.

The called subscriber having ascertained by test that the call is from the left, manipulates the catch 28 and allows the receiver-hook to move upward to the position shown in Fig. 4, thus closing the contacts of the pole-changer 31 and connecting contacts 11', 16, and 15, while opening contacts 12, 13, and 14.

The stations shown in Figs. 3 and 4 being now connected, with the station shown in Fig. 2 between them, the talking-circuit may be traced from the ground at station shown in Fig. 3 to wire 33, binding-post 2, wire 34, the primary of the induction-coil 7, wire 35, contacts of the pole-changer 30, wire 31', transmitter 10, primary battery 26, wire 25, wire 37, contact 13, contact 12, wire 17, binding-post 3 to line-wire. The circuit is extended at the station shown in Fig. 2 from line-wire through binding-post 1, wire 22, electromagnet 23, wire 22, contacts 14 and 12, wire 17, binding-post 3 to main-line wire 4, so that at the station the electromagnet 23 is energized, and the receiver cannot be raised to allow over-hearing of the conversation. At the station shown in Fig. 4 the circuit extends from the left over main line 4, binding-post 1, wire 22, wire 43, contact 15, contact 16, wire 38, transmitter 10, battery 26, wire 25, pole-changer 31, wire 36, the primary of the induction-coil 7, wire 34, binding-post 2, and ground-wire 33. From this it will be seen that the batteries 26 are connected in series, and these batteries are of sufficient strength to energize all of the electromagnets 23 at the intermediate stations.

Returning now to station shown in Fig. 3, it will be observed that the line to the left of

said station is wholly disconnected from the station and cannot overhear any conversation. From binding-post 1 runs wire 22 to electromagnet 23, thence by wire 22 to contact 14, which is open. From wire 22 runs wire 43 to contact 15, which is also open.

At station No. 4 the line to the right is entirely cut out from station 4. From binding-post 3 runs wire 17 to contact 12, which is open, so that no current can pass to or from the right of station 4.

When any subscriber wishes to call any subscriber to his left, the receiver is removed from the hook and catch 28 is moved to release position, as shown in Fig. 4, thus permitting the receiver-hook to raise to the highest point. A signaling-circuit is now established from ground-wire 33, binding-post 2, wire 34, wire 40, call-bell 9, condenser 19, magneto-generator 8, wire 41, contact 11', contacts 16 and 15, wire 43, wire 22, binding-post 1, and out to main line 5 to the left, where it will pass through one or more stations having their parts in normal position, as indicated in Fig. 2. At each of these stations the current will enter through main line 4 from the binding-post 3, wire 17, contact 12, contacts 13 and 11', wire 41, magneto-generators 8, condenser 19, wire 40, call-bell 9, wire 40, wire 34, binding-post 2 to ground-wire 33. From this it is evident the main line can be divided into any desired number of sections, and if there are ten subscribers connected on the same line subscribers 2 and 4 may monopolize that portion of the line between them, while at the same time subscribers 5 and 7 or any other two subscribers beyond subscribers 2 and 4 may monopolize any portion of the line at the same time.

It is further evident that every subscriber between two stations in communication with each other is locked out and cannot overhear any conversation, nor can he send any signal along the line until the electromagnet 23 at his station is deenergized.

Having thus described the invention, what is claimed is—

1. In party-line telephone systems, a receiver-hook-locking magnet at each station, all of said magnets being connected in series with a line-wire without including any of the local telephone or signaling apparatus, a return common to all of the stations, a local talking-circuit at each station normally disconnected from the return, and held disconnected by the receiver-hook-locking magnet when the line is energized, a receiver-

hook, a plurality of connections under the control of the receiver-hook, and means for limiting movement of the receiver-hook to close signaling and talking circuits from the line-wire on either side of the station to the common return, and to cut out the line-wire connection on the opposite side.

2. In a party-line telephone system, a line-wire connecting the stations in series, a ground or common return to which the stations may be connected in multiple arc, a receiver-hook, a plurality of contacts under the control of the receiver-hook and means serving to limit movement of the latter to form a connection from the line-wire on one side of the station through the station to the common return and to cut out the connection with the line-wire on the opposite side, and on extended movement to form a similar connection with the said opposite line-wire and to cut out the previous connection, a receiver-hook-locking magnet in series with the line-wire, and a manually-operable catch for permitting extended movement of the receiver-hook.

3. In party-line systems, a plurality of substations, a line-wire extending from station to station, and serially connected thereto, a ground or common return, there being at each of the substations a receiver-hook, a receiver-hook-locking magnet, a plurality of contacts under the control of the receiver-hook, and telephonic and signaling devices, the receiver-hook-locking magnet being normally connected in series with the main line, and the telephonic apparatus being normally disconnected from the common return and being held disconnected while the electromagnet is energized, limited movement of the receiver-hook connecting the station to the common return and cutting off the line connection on one side of the telephone, and movement to a greater extent connecting the station to the line on the opposite side.

4. In telephony lock-outs, the combination with a receiver-hook, of an electromagnetically-controlled catch for locking the receiver-hook from any movement, and a second manually-manipulated catch adjustable to permit greater or less movement of said receiver-hook.

In testimony that I claim the foregoing as my own I have hereto affixed my signature in the presence of two witnesses.

JAMES H. GORDEN.
